(73) Assignee: **Double Team Inc.**, Daly City, CA (US)

(57) **CLAIM**

(**) Term: **14 Years**

The ornamental design for a lid assembly with a reclosable drink opening, substantially as shown and described.

(21) Appl. No.: **29/305,315**

DESCRIPTION

(22) Filed: **Mar. 18, 2008**

FIG. 1 is a top perspective view of the lid assembly of this invention with the sliding member thereof in its closed position;

(51) LOC (9) Cl. **07-01**

FIG. 2 is a top view of the lid assembly of FIG. 1;

(52) U.S. Cl. **D7/396.2; D7/900; D7/396.1; D9/435**

FIG. 3 is a bottom perspective view of the lid assembly of FIG. 1;

(58) **Field of Classification Search** **D7/396.2, D7/396.1, 387, 900, 396, 392.1; D9/435, D9/455, 434, 449, 445, 438, 441, 439, 436, D9/443, 447; 206/807; 215/235, 237; 220/254.1, 220/254.3, 345.3, 254.6, 270; D20/28; 222/480**

FIG. 4 is a view in elevation of the lid assembly of FIG. 1 along line 4—4 of FIG. 2;

See application file for complete search history.

FIG. 5 is another view in elevation of the lid assembly of FIG. 1 along line 5—5 of FIG. 2;
